UNITED STATES PATENT OFFICE.

HARRY C. YOCUM AND MARTIN V. KACER, OF ST. LOUIS, MISSOURI.

PACKING-CASE.

SPECIFICATION forming part of Letters Patent No. 445,869, dated February 3, 1891.

Application filed April 23, 1890. Serial No. 349,173. (No model.)

To all whom it may concern:

Be it known that we, HARRY C. YOCUM and MARTIN V. KACER, both of the city of St. Louis, in the State of Missouri, have invented 5 a certain new and useful Improvement in Packing-Cases, of which the following is a full, clear, and exact description, reference being had to the accompanying drawings, forming part of this specification.

10 This case is made of corrugated veneer nailed to stiff frames. The invention will be described as applied to an egg-case; but it is obvious that the same principle may be applied to cases for other purposes.

15 Figure I is a perspective view of one of the rectangular frames, of which there are three, one at each end and one at the middle of the case. Fig. II is a perspective view of one of the ends or middle partition detached in condition for shipment, the case being adapted for shipment in sections, which are packed in solid form for shipment, the parts all being flat when disconnected. Fig. III is a transverse section of the case at III III, Fig. IV.

25 Fig. IV is a longitudinal section of the case at IV IV, Fig. III.

2 3 are rectangular frames formed of four bars 1, connected at their ends in any suitable manner—for instance, as shown in Fig. I.

30 The case in the instance shown and described has three of these frames—namely, one at each end and one at the middle, as seen at 2 2 and 3, the ends of the case being marked 2 and the middle partition 3. The bottom

35 and top and the walls of the case, in addition to the frames 1, are formed of corrugated veneer. The ends 2 and partition 3 have sheets 4 of equal or about equal are with the frames 1, and are fixed to the frames with tacks or 40 other nails. The partition 3 has a sheet upon each side, while the ends 2 may properly, as shown, have a sheet only upon the inner side. (See Fig. IV.) The side sheets 5, bottom sheets 6, and top sheet 7 may extend the whole

45 length of the case, and are nailed to the edges of the end and middle frames 1. 8 are strips or hoops, of hickory or other tough wood, or of metal, which are lapped around the case over the sheets 5, 6, and 7 and nailed (through 50 the sheets) to the edges of the frames 1. The

ribs and grooves of the veneer may run in any preferred direction. The purposes of the corrugations are to give stiffness to the sheets and to allow free ventilation. The case is open at all the corners for the entrance and 55 exit of air, as the corrugated material cannot be tightly fitted at the edges. The grooves of the veneer allow the free passage of air between the walls and any box or tray which may be in the case. 60

The cases will be both cheap and strong, for the veneer is produced very cheaply, and the frames 1 may be made from refuse scraps from the planing-mills or other cheap material. The strength of the case results from 65 the grain of the frames running parallel with the walls and the flexible nature of the veneer, which will bend freely, but not break, except under extreme violence.

In shipping the material of which the cases 70 are made it is preferred that the sheets 4 should be nailed to the frames 2 and 3, and the hoops 8 also loosely nailed to the frames, when a number of the frames with the sheet or sheets 4 and hoops 8 attached may be laid 75 flat upon each other and secured together in any suitable way. The side, bottom, and top sheets 5 6 7 may be laid flat upon each other and secured together in the same manner, so that material for a large number of cases may 80 be put in a small space. The cases may be put together without skilled labor and with no tool but a hammer.

We claim as new and of our invention—
A shipping-case constructed of open frames 85 2 3, having corrugated pieces of veneer 4 applied to them to close the openings, corrugated pieces of veneer 5 6 7, applied to the edges of the frames forming the sides of the case, the grooves of the pieces of veneer on 90 the side next the frames forming air-inlets to the inside of the case, and binding-hoops 8, securing the pieces 5 6 to the frames, all substantially as and for the purpose set forth.

HARRY C. YOCUM.
MARTIN V. KACER.
